The ornamental design for a purse ring for use in the fishing industry, as shown and described.

DESCRIPTION

FIG. 1 is an elevational view of a purse ring for use in the fishing industry, showing my new design;

FIG. 2 is a view thereof from the side opposite that shown in FIG. 1;

FIG. 3 is a view thereof from the left of FIG. 1, with the gate thereof thrown open;

FIG. 4 is a view thereof from the right of FIG. 1, with the gate thereof closed;

FIG. 5 is a top plan view thereof; and,

FIG. 6 is a bottom plan view thereof.
